UNITED STATES PATENT OFFICE.

PRENTISS R. CRALL, OF COLUMBUS, OHIO.

LOCK FOR STOP-BOXES.

1,307,346.

Specification of Letters Patent. Patented June 24, 1919.

Application filed December 21, 1918. Serial No. 267,854.

To all whom it may concern:

Be it known that I, PRENTISS R. CRALL, a citizen of the United States, residing at Columbus, in the county of Franklin and State 5 of Ohio, have invented certain new and useful Improvements in Locks for Stop-Boxes, of which the following is a specification.

This invention relates to the improvement of locks for stop boxes such as are ordinarily 10 employed in connection with water and gas service pipes.

The objects of my invention are to provide an improved means for locking the cap or top member of a stop box in connection with the top of said box; to so construct 15 and arrange the parts of my improved locking device that access to the locking bolt which is ordinarily employed is prevented unless the sealing member is broken.

20 It is well known that a plumber or other person having a suitable tool may readily remove the locking bolt which is ordinarily employed in stop boxes thereby permitting of the removal of the cap or top plate and of 25 the insertion into the stop box of a key or other tool for the purpose of turning the valve which controls the supply of water or gas to certain premises and it is an object of my invention not only to prevent the unauthorized turning of the valve but to show at 30 a glance whether or not the lid of the stop box has been removed.

The preferred embodiment of my invention is shown in the accompanying sheet of 35 drawing wherein similar characters of reference designate corresponding parts and wherein,

Figure 1 is a view in elevation of the upper portion of a stop box having my improved locking or sealing device in connection therewith,

Fig. 2 is a vertical section of the same,

Fig. 3 is an enlarged vertical section of the ordinary stop box bolt and portions of 45 the parts connected thereby, my improved device being shown in its locked or sealed position, and

Fig. 4 is a face view of the locking washer or disk which I employ in the manner hereinafter described.

Referring to the drawing 1 represents the usual cylindrical stop box such as is ordinarily used by gas and water companies and through which access is gained to the 55 valve which controls a supply of water and gas to the adjoining premises. The upper

and otherwise open end of the stop box body is provided with the usual inwardly projecting horizontal lug 2. Three (3) represents the separately formed lid or cap plate 60 of the stop box which is designed to cover said stop box and which is formed with a suitable depression 4. This depression or seat 4 is designed to receive the enlarged head 5 of a bolt or screw 6, the threaded portion of which is adapted to engage opposing openings in the depressed portion 4 of the cap 3 and in the box lug 2, the latter being a threaded opening. In carrying out my invention I employ about the stem of the bolt 70 6 adjacent its head 5 a locking disk 7. This disk has a short collar like member 8 projecting downward from about its central opening when the outer or marginal portion 75 of the disk is formed with a plurality of radial cuts or incisions 9 which result in the production of radial spring tongues 10. These spring tongue portions as indicated more clearly in Fig. 3 of the drawing are preferably beveled or gradually reduced in 80 thickness toward their outer ends and are bent downward at a suitable incline from the body of the disk. The disk 7 or that portion thereof which immediately adjoins the downturned member 8 bears upon a 85 washer 11 which washer has an outwardly extending base flange 12, the circumferential outer side of which is beveled as indicated in the drawing. A washer 11 is seated upon the floor of the depression 4 in the cap plate. 90 Thirteen (13) represents a locking or sealing cap which is preferably of inverted cup shape and which is designed as a housing for the upper portion of the bolt and its head together with the disk 7 and washer 11. In 95 forming this locking cap I provide on its inner face near its lower end a continuous internal shoulder 14, the internal surface of the cap from the level of its shoulder to the cap base being beveled internally as indicated at 15; this bevel was corresponding with and contacting with the beveled outer surface of the washer flange 12 when the locking cap is in its locked position. When 100 the locking cap is pressed into the locked position shown in Figs. 2 and 3 of the drawing it will be understood that the internal beveled surface 15 of the cap is intended to come into contact with the ends of the locking tongues 10 causing the latter to be 105 depressed or sprung downward and inward until they have reached the level of the

shoulder 14 at which point said tongues will be permitted to spring outward and engage the shoulder 14. This engagement of the shoulder 14 and the spring locking tongues 5 will serve to clearly lock the cap member 13 from removal from its locked position about the bolt head. It is obvious that the presence of the flanged washer 8 will prevent manipulation of the spring tongues from 10 outside the cap by the insertion of any instrument beneath the edge of the cap.

The locking cap being in the position described and shown in the drawing it will be readily understood that access to the head 15 of the bolt which is necessary to disconnect the cap plate 3 and the stop box is prohibited. In fact the nature of my improved lock is such that access to the head of the bolt can only be attained by breaking the 20 cap member 13. These cap members it will be understood may be made of comparatively cheap material such as cast iron which will admit of their being broken by representatives of the gas or water companies 25 who are authorized to turn on or off water from certain premises, without incurring more than a nominal expense. It will be further understood that the finding of a stop box with a broken cap member 30 will at once be an indication that some unauthorized person has gained access to the valve which controls the supply of water to the adjacent premises, whereas under the present practice of exposing the head of the 35 locking bolt permits anyone to gain access to the stop box without leaving any indication that such access has been gained.

From the above description it will be seen

Copies of this patent may be obtained for five cents each, by addressing the "Commissioner of Patents, Washington, D. C."

that my device is simple in construction, can be produced at low cost of manufacture and 40 will result in a great saving to water and gas supply companies.

What I claim is:

1. In a locking device for stop boxes, the combination with a stop box body, a separately formed top plate therefor and, a bolt adapted to unite said top plate and stop box, of a locking member beneath the head of said bolt and a sealing cap having internal means for engagement with said locking 45 member when the cap is pressed downward over the head of the bolt.

2. In a locking device for stop boxes, the combination with a stop box body, a top plate therefor and a bolt uniting said top 50 plate and stop box, of a locking disk mounted on said bolt beneath the head of the latter, said disk being provided with spring tongues, and a sealing cap having a shoulder on its inner wall surface adapted when said 55 cap is pressed downward over said bolt head to engage said spring tongues.

3. In a locking device for stop boxes, the combination with a stop box body, a top plate therefor and a bolt uniting said top 60 plate and stop box, of a locking disk mounted on said bolt beneath the head of the latter, said disk being provided with spring tongues, a washer also mounted on said bolt beneath said spring locking disk and a sealing 65 cap having an internal shoulder which is adapted to be engaged by the said spring tongues when said cap is in place over the head of the bolt.

In testimony whereof I affix my signature. 70
PRENTISS R. CRALL. 75
